UNITED STATES PATENT OFFICE.

CHARLES GUZY, OF NEW YORK, N. Y.

SEWING-MACHINE HOPPER.

1,257,850.

Specification of Letters Patent. Patented Feb. 26, 1918.

Application filed October 27, 1916. Serial No. 126,121.

To all whom it may concern:

Be it known that I, CHARLES GUZY, a citizen of the United States, residing at New York, in the county of New York and State of New York, have invented certain new and useful Improvements in Sewing-Machine Hoppers; and I do hereby declare the following to be a full, clear, and exact description of the invention, such as will enable others skilled in the art to which it appertains to make and use the same.

This invention relates to sewing machine hoppers, and more particularly to that type of receptacles carried by a sewing machine bed to receive the work from the sewing machines commonly used in large establishments.

An object of this invention is to provide a hopper which may be attached to a sewing machine to receive the work from the machine and in having said hopper so arranged as to return the work to the operator in the order in which the work was done, so that the operator may handle the garments in their successive steps in regular order.

A further object of this invention is a provision of a hopper of compact design which permits each sewing machine having its individual hopper, to thereby keep the work of the operators separate.

A further object of this invention is a hopper having an inclined bottom which feeds the work back to the operator by gravity.

A further object of this invention is a provision of a hopper for a sewing machine, which may have the receiving end thereof placed behind the sewing machine so as to receive the work from the machine, said hopper having an inclined bottom and so arranged as to feed the work back to the operator in the order in which it had been worked upon, and the further provision of a container which may be hingedly secured to said hopper to serve as a stop or closure for the end of the hopper and to further receive the unfinished work.

Further objects will be apparent from the following specification, appending claims and drawings, in which—

Figure 1 is an end elevation, partly in section, showing the relative arrangement of sewing machines so equipped with these hoppers,

Fig. 2 is a plan view of two sewing machines showing the hoppers attached thereto,

Fig. 3 is a perspective view of the hopper detached, showing the container swung to permit the removal of the material from the hopper, and

Fig. 4 is a transverse sectional view through the container.

In factories where large numbers of sewing machines are used, having said sewing machines so arranged as to receive power from a common shaft, it is desirous of having means for taking care of the partly finished work from the operators in such a method as to prevent the work of the opposite operator becoming mixed, and where garments are made which require several steps in the production thereof, it is customary for the operator to work on said garments by producing the first step in each garment, and then passing each garment through the machine successively for the following steps until it is finished, at which time the individual garments may be separated from each other. In this invention, means are provided and shown, for taking care of the partly finished work by receiving the garments in a partly finished form and returning the same to a convenient position for the operator to handle in passing through the machine for the second operation.

Referring to the drawings in which the several features of this invention are clearly shown, 10 and 11 indicate sewing machine beds on which the sewing machines 12 are placed. These beds may be supported by the usual frames 13, and supported by these frames are the pulleys 14 and 15, of which the pulleys 14 receive the belts 16 which drive the sewing machines, while the pulleys 15 receive the belts 17 which also pass about the pulleys 18 on a common drive shaft 19. The pulley 15 drives the shaft supporting the pulley 14, but the usual type of clutch mechanism may be employed for connecting the pulley 14 to the driven shaft, and for operating such clutch mechanism I provide a treadle 20, which may be pivotally mounted as at 21 to the bearing block 22. This treadle may be connected to the clutch member as by a chain or other connecting means, 23.

The common drive shaft 19 may be supported in the usual manner, as by standards, of which one is shown as at 24, and this shaft may receive its power from any prime mover such as an electric motor or the like.

The sewing machine beds 10 and 11 are in spaced relation but are arranged in parallel relation as in common practice to receive hoppers 25 and 26 therebetween. These hoppers

- 5 are so arranged as to permit interchangeability between the sewing machine beds, and will preferably be of a similar construction having a raised side wall 27 along one side thereof, the corresponding wall 10 28 along the back thereof, and a diagonally disposed wall 29 which abuts against a corresponding wall of the adjacent member. The bottom 30 is inclined from the side walls 27, 28 and 29, and is of such a pitch as to 15 return the articles placed therein to the operator through the open end 31 of the chute. The side wall 27 may be plane, but the opposite wall 32 is curved substantially as shown, to provide room for the clutch 20 mechanism and pulleys of the sewing machine as well as to afford room for the operator's knees.

The open end of the chute 31 is normally closed by a container 33 which has one wall

- 25 thereof hingedly secured as at 34 to the lower end of the side wall 27 and this container may have a series of compartments 35, formed therein to receive work to be handled by the machine. The opposite wall of this 30 container has a lug 36 formed therein, with which a fastening member 37 carried by the chute co-acts in holding said container in locked relation to the chute to thereby cause one of the partitions 38 to form a closure for 35 the end of the chute. The container has a cover 39 hingedly secured thereto which may be swung to overlie the several compartments of the container or to assume a position against the end wall of said container, 40 and the container is further provided with legs or supports 40 to keep the bottom of the container in spaced relation to the floor. The function of hingedly securing said container to the chute is to prevent the containers 45 33 of the several sewing machines from becoming mixed as is common in factories where large numbers of employees are, and by swinging said container to an open position the contents of the chute may be 50 easily removed.

It is thought that the application and utility of such a chute as this is clearly seen in view of the foregoing, and that the foregoing description clearly defines the general 55 principle of this type of chute. Various modifications may be made within the scope of the pending claims without departing from the spirit of the invention, and no limitation is implied by the limited showing of the drawings.

Having thus described this invention, I claim

1. A hopper for attachment to a work table comprising an inclined bottom to feed 65 work toward the lower end of the bottom, an

enlarged upper end rising behind the rear edge of the work table, a reduced lower end underlying the forward edge of the work table, and said hopper receiving work from over the rear edge of the work table and 70 feeding it to a point under the front edge for subsequent treatment.

2. A hopper for attachment to a work table comprising an enlarged upper end positioned behind the rear edge of the work 75 table, one edge of said enlarged upper end being disposed at an acute angle with respect to the rear edge of the work table, to afford clearance for a similarly shaped portion of an adjacent hopper, an inclined bottom extending forwardly from said enlarged rear end under said work table, pitched to feed work to the lower end of said bottom, and a forward reduced lower end underlying the forward edge of said work table to 80 receive and gather the work fed over the rear edge of the work table for convenient handling from a point in front of said work table.

3. A hopper for attachment to work tables 90 arranged in spaced and parallel relationship, comprising an enlarged upper end positioned between the work tables, having side walls rise above the level of the work tables, an inclined bottom leading forwardly 95 from said enlarged upper end, side walls shaped to receive the edges of said inclined bottom member, a reduced lower end to gather work fed into said hopper under the line of the forward edge of the work 100 table, and some of the side walls of said enlarged upper end being shaped to receive corresponding side walls of adjacent hoppers carried by said work tables.

4. A hopper of the class described comprising side walls, an inclined bottom between said side walls, one of said side walls being curved to surround the required space under a sewing machine bed, a container hingedly carried by said hopper at the edge 11 of one of the side walls thereof, said container having a series of compartments formed therein, a cover hingedly carried by said container and means for holding said container in locked relation with respect to 11 said hopper.

5. A structure of the class described, comprising in combination, work tables disposed in parallel and spaced relationship, hoppers carried by said work tables, having inclined 12 bottoms and converging side walls from the rear to the front, and said hoppers having the upper edges of the rear edge of the inclined bottoms, and side walls between the work tables formed to afford a maximum 12 width, equal to the space between said work tables and a length equal to that of each individual work table.

6. A structure of the class described comprising in combination work tables in spaced 13

and parallel relationship, hoppers secured to said work tables having enlarged irregularly shaped upper ends rising between said work tables, each of said hoppers extending 5 along predetermined sections of the rear edges of said work tables, each of said hoppers having portions thereof extend within the limits of the adjacent one, and each of said hoppers having the rear wall obliquely 10 disposed to allow the rear walls to abut in the adjacent hoppers.

7. A structure of the class described comprising in combination, work tables disposed in spaced and parallel relationship, hoppers 15 carried by said work tables, each of said hoppers having an enlarged upper end disposed between the inner edges of the work tables, inclined bottom members leading from said enlarged upper ends to reduced lower 20 ends under the outer edges of said work tables, side walls shaped to receive the edges of said inclined bottom members, and rear walls of said hoppers positioned to abut and form a partition between the inner edges of 25 said work tables to keep the work done on the work tables separated.

8. A structure of the class described, comprising in combination, a work table, a hopper secured thereto, said hopper having

an enlarged upper end positioned to receive 30 work passed over the rear edge of said work table, a reduced lower end under the forward edge of said work table to collect work fed into said hopper and an inclined bottom to feed the work from the enlarged upper 35 end to said reduced lower end.

9. A hopper for attachment to a work table comprising an enlarged upper end to receive work passed over the rear edge of the work table, a reduced lower end to 40 gather the work fed into the enlarged upper end, under the forward edge of the work table, an inclined bottom for feeding the work from the enlarged upper end to the reduced lower end, a receptacle hingedly secured to said hopper at the lower end, a partition in said receptacle forming a closure 45 for the lower end of said hopper, and a cover hingedly carried by said receptacle to overlie said receptacle and the lower end of 50 said hopper when swung to serve as a cover.

In testimony whereof I affix my signature in presence of two witnesses.

CHARLES GUZY.
